UNITED STATES PATENT OFFICE.

WILLIAM A. CHRYST, OF DAYTON, OHIO, ASSIGNOR TO THE DAYTON ENGINEERING LABORATORIES COMPANY, A CORPORATION OF OHIO.

IGNITION SYSTEM.

1,391,460.

Specification of Letters Patent. Patented Sept. 20, 1921.

Application filed September 7, 1917. Serial No. 190,150.

To all whom it may concern:

Be it known that I, WILLIAM A. CHRYST, a citizen of the United States of America, residing at Dayton, county of Montgomery, 5 and State of Ohio, have invented certain new and useful Improvements in Ignition Systems, of which the following is a full, clear, and exact description.

This invention relates to an improvement 10 in ignition systems, and more particularly to that part of ignition systems which includes the timing and distributing mechanism.

One of the objects of the present invention is to provide means for the adjustment and 15 mounting of certain parts of the timing mechanism of the ignition system, whereby the adjusted position of said parts may be readily secured and maintained with precision.

20 Further objects and advantages of the present invention will be apparent from the following description, reference being had to the accompanying drawing, wherein a preferred form of one embodiment of the present invention is clearly set forth.

In the drawing:

Figure 1 is a view in side elevation of a timing and distributor unit included in an ignition system, a portion of the casing being 30 cut away to show the internal mechanism.

Fig. 2 is a top plan view of the timing mechanism.

Figs. 3 and 4 are detail fragmentary views 35 of the locking device for the timer cam.

Figs. 5, 6 and 7 are detail views of certain parts of said locking device.

Referring to Fig. 1, there is disclosed what 40 may be termed a timing and distributing mechanism, which is adapted to control the time of occurrence and the distribution of the sparking impulses to an engine.

This timing and distributing device is 45 preferably driven by an engine, at any predetermined ratio of speed, through a connection with the shaft 20. This shaft 20 projects into the casing 21 and is secured to a plate or disk 22, which in turn carries the pins 23. These pins 23 form pivot points for the weights 24, which are mounted 50 thereon in any suitable manner. Each of the weights 24 engage with a spider, carried by the stub shaft or carrying element 26; this arm or element in the present instance being hidden from view by the assembly of 55 the weights.

This cam carrying element 26, together with the weights 24 and certain other elements not disclosed in the present drawing, form an automatic control mechanism, whereby the time of the spark is varied in accordance with the speed of the engine, by the relative movement or adjustment of the carrying element to the shaft 20.

This automatic control mechanism, above referred to, forms a part of the subject matter of the patent issued to Charles F. Kettering and William A. Chryst, No. 1,303,831 dated May 13, 1919, and no further description of these elements is deemed necessary in the present application, except where description is necessary to clearly bring out the features of the present invention.

The cam carrying element 26, as has been stated heretofore, fits over the stub shaft 27, and is provided with a reduced head portion 28, which is tubular in conformation and suitably slotted as at 29, so as to provide a plurality of expansible and slightly resilient fingers 30.

This reduced head portion of the cam 80 carrying element 26 supports the cam element 31, which is provided with suitable lobes 32 to actuate the movable contact element 33 (see Fig. 2), to break the ignition circuit at the contacts 34 and 35; that is, the 85 contact plate 33 is provided with a spring 36 which tends to normally maintain the contact plate 33 in circuit closing position relative to the contact 35.

Now as soon as the cam rotates, the lobes 90 carried thereby will strike the same and force it away against the tension of the spring 36. As soon as the cam will have passed out of contact with the contact plate 33, a spring 36 will immediately return said 95 contact plate to circuit closing position.

The cam 31 is provided with a reduced head portion or shank 37, which is provided with a flat on each side as at 41, to prevent relative movement of the distributor rotor 100 38, which is mounted directly thereon.

It is well known to those skilled in the art, that the adjustment of the timer cam relative to the movable contact 33, must be made with precision, and that it frequently becomes necessary to change this adjustment to compensate for wear, varying engine conditions, and certain other well known conditions.

The adjustment of the timer cam also makes 110

advisable a corresponding adjustment of the rotor of the distributor, so that the timer cam and the rotor will operate in a determined relation, and it is important that this 5 relation be maintained.

In order to secure and maintain the proper adjustment of the cam and the rotor, there 10 is provided in the present form of the invention, a bolt 45 threaded at one end as at 46, to engage with the threaded opening 47 formed in the cam carrying element 26. This bolt or screw 45 is grooved intermediate its ends as at 48, to provide a seat for the ring 49. This bolt 45, as stated above, is 15 threaded at its lower end and forms the controlling element of the locking device.

Between the grooved portion 48 and the head of the bolt 45, a sleeve 50 is positioned, which is preferably provided with an externally tapered surface. The distance between the groove 48 and the head of the bolt 45, is greater than the length of the sleeve 50, so that the bolt 45 may be moved relative to the sleeve, for the purpose described here- 25 inafter.

By referring to Figs. 3 and 4 it will be noted that when the cam 31 has been placed on the expansible shank of the cam carrying element 26, and adjusted to its proper position relative to the contact plate 33, the bolt 30 45, carrying the tapered sleeve 50 and the ring 49, is forced down through the shank portion of the cam carrying element 26, and the threaded end of said bolt is screwed 35 home as is shown in Fig. 3.

When the bolt 45 is screwed into the cam carrying element 26, the tapered sleeve 50 tends to engage the fingers or prongs of the expansible shank, and to force the same outwardly into frictional contact with the 40 cam 31.

Inasmuch as the bolt 45 turns relative to the sleeve 50, there is no tendency for an imperfect contact between the fingers of the 45 shank and thus an even distribution of pressure is exerted against each of the prongs of said shank.

It will further be seen, by referring to the Figs. 3 and 4, that the initial movement of 50 the sleeve 50 is in a direct downward direction, that is the sleeve has no turning effect, and therefore efficient and permanent expansion of the prongs is effected by the forcing of this sleeve downwardly into the interior of the shank.

When it is desired to release the cam for the purpose of readjustment, or for complete removal, the bolt 45 is unscrewed and when said bolt works upwardly, as shown in 60 Fig. 4, the ring 49, carried in the groove 48, engages the lower end of the tapered sleeve 50 and will force the same out of its locking position, so as to readily permit the readjustment of the cam or the complete removal 65 thereof from the cam carrying element 26.

In order to positively retain the ring 49 within the groove 48, when the stud 45 is unscrewed to adjust the cam carrying element, the lower, inner portion of the tapered ring 50 is beveled off as at 51, which beveled portion will tend to press the ring 49 and thereby prevent the same from being forced out of the groove 48. 70

From the above description it will be seen that the ring 49 tends to positively force the 75 said locking sleeve 50 upwardly for the releasing movement, while the head of the bolt 45 tends to positively drive said sleeve into its locking position.

By referring to Fig. 1, the arrangement of 80 the rotor on the cam 31 is clearly shown, and it will be apparent that if the cam is adjusted to any determined position, a consequent adjustment of the rotor must be made, inasmuch as this rotor fits over a portion of 85 the cam 31 and is held against a relative movement by 2 flat sides, formed in the opening of the rotor.

While the form of mechanism herein shown and described constitutes a preferred 90 form of embodiment of the invention, it is to be understood that other forms might be adopted, all coming within the scope of the claims which follow.

What I claim is as follows:

1. In a device of the character described, the combination with a rotatable cam carrying element having an expansible shank; of a cam supported on said shank; a member for expanding said shank; and means for forcing said expanding member into said shank, said means being capable of movement independently of said expanding member.

2. In a device of the character described, the combination with a rotatable cam carrying element having an expansible shank; of a cam supported on said shank; a member for expanding said shank; and means for forcing said expanding member into said shank, said means being capable of movement independently of said expanding member, and said means having provisions for effecting removal of said expanding member when said means is moved from said shank.

3. In a device of the character described, the combination with a rotatable cam carrying element having an expansible shank; of a cam supported on said shank; a tapered sleeve adapted to fit within said shank to 120 expand the same; and a bolt passing through said sleeve and having threaded connection with the cam carrying element, both bolt and sleeve capable of axial movement, but the bolt capable of rotation independently of said sleeve.

4. In a device of the character described, the combination with a driving shaft; of an ignition device, including a cam carrying element having an expansible shank; a cam 130

adapted to fit on said shank; a locking sleeve; a bolt carrying said sleeve and adapted to force the same into the shank of the cam carrying element to expand it and lock the cam in adjusted position, said bolt having provisions to force the sleeve out of its locking position to release the cam.

5. In a device of the character described, the combination with a driving shaft, of an 10 ignition device including a cam carrying element having an expansible shank; of a cam adapted to fit on said shank; a tapered locking sleeve; a bolt carrying said sleeve and provided with a head adapted to engage the 15 sleeve and to force the same into engagement with the shank of the cam carrying element and expand said shank and thereby lock the cam in adjusted position, said bolt having also a groove disposed at a distance 20 from the head to enable the sleeve to be disposed between the groove and the head; and a ring located in said groove and adapted to engage the sleeve, when the bolt is unscrewed from the cam carrying element.

25 6. In a device of the character described, the combination with a driving shaft, of an ignition device including a cam carrying element having an expansible shank; of a cam adapted to fit on said shank; a tapered 30 locking sleeve having an internally tapered portion; a bolt having screw threaded engagement with the cam carrying element and having a head adapted to engage the sleeve and to force the same into the shank 35 of the cam carrying element and to expand said shank thereby to lock the cam in adjusted position, said bolt having a groove located at a distance from the head such that the sleeve may be disposed on the bolt 40 between the groove and the head; and a split ring located in the groove and adapt-

ed to engage the sleeve when the bolt is unscrewed from the cam carrying element whereby to effect the removal of the sleeve from the shank portion, said internally tapered portion of the sleeve engaging the ring whereby the ring will be maintained in position in the groove as the ring effects the removal of the sleeve from the shank.

45 7. In a device of the character described, the combination with a driving shaft; of an ignition device including a cam carrying element having an outwardly expansible portion; a cam adapted to fit over said expansible portion; movable expanding means for 50 expanding said expansible portion; and screw-threaded means engaging the cam carrying element for moving the expanding means into engagement or out of engagement with said expansible portion, said 55 screw-threaded means being rotatable independently of said expanding means.

60 8. In a device of the character described, the combination with a driving shaft; of an ignition device including a cam carrying element having a plurality of outwardly expansible portions; a cam adapted to fit over said expansible portions; an axially movable expanding sleeve for expanding said 65 expansible portions; and screw-threaded 70 means passing through said sleeve and engaging the cam carrying element and having provisions for moving the expanding means into engagement or out of engagement with said expansible portions, said 75 screw-threaded means being rotatable independently of said expanding means.

In testimony whereof I affix my signature.
WILLIAM A. CHRYST.
